DESIGN FOR A PEDESTAL CLOCK

Joseph H. Fronenberg, Los Angeles, Calif.

Application October 26, 1936, Serial No. 65,495

Term of patent 14 years

To all whom it may concern:

Be it known that I, Joseph H. Fronenberg, a citizen of the United States, residing at Los Angeles, in the county of Los Angeles and State of California, have invented a new, original, and ornamental Design for a Pedestal Clock, of which the following is a specification, reference being had to the accompanying drawing, forming part thereof.

Fig. 1 is a front elevational view, in perspective, of a pedestal clock showing my new design; and

Fig. 2 is a side elevational view thereof, in perspective.

I claim:

The ornamental design for a pedestal clock, as shown.

JOSEPH H. FRONENBERG.
